WASTE RECEPTACLE

Donald Doman, Janesville, Wis., assignor to The Parker Pen Company, Janesville, Wis., a corporation of Wisconsin

Filed June 4, 1964, Ser. No. 80,282

Term of patent 14 years

(Cl. D58—17)

FIGURE 1 is an elevational view of a waste receptacle, embodying my new design, the side opposite being the same in appearance;

FIGURE 2 is an elevational view looking from the right of FIGURE 1, the opposite side being the same in appearance;

FIGURE 3 is a top plan view;

FIGURE 4 is a bottom plan view; and

FIGURE 5 is an enlarged fragmentary sectional view thereof taken on the line 5—5 of FIGURE 1 with a portion of the waste receptacle being broken away for convenience of illustration.

I claim:

The ornamental design for a waste receptacle, substantially as shown and described.
